UNITED STATES PATENT OFFICE.

FRANK W. MILLER, OF CHICAGO, ILLINOIS, ASSIGNOR OF ONE-HALF TO CLARENCE D. BAUERS, OF CHICAGO, ILLINOIS.

BOILER WASHING AND FILLING SYSTEM.

1,109,354.

Specification of Letters Patent.

Patented Sept. 1, 1914.

Application filed May 27, 1912. Serial No. 700,045.

To all whom it may concern:

Be it known that I, FRANK W. MILLER, a citizen of the United States, residing at Chicago, in the county of Cook and State 5 of Illinois, have invented certain new and useful Improvements in Boiler Washing and Filling Systems, of which the following is a specification.

This invention relates to boiler washing 10 and filling systems and aims in general to utilize the heat of the blow-off products of a boiler for heating water to suitable temperatures for washout and refilling purposes.

15 One of the primary objects of the present invention is to effect a saving in the amount of water employed in washing out boilers by collecting the wash water from the roundhouse pits and, subsequently, utilizing 20 this water again, after it has been cleansed, for washout purposes, thereby effecting considerable economy over the operation of plants in which the wash water from the roundhouse pits is permitted to escape to 25 the sewer.

Another object is to heat the wash water 30 in the washing water reservoir by means of hot blow-off water and, at the same time, to prevent contamination of the washing water 35 by the dirty blow-off water, this result being accomplished by passing the blow-off water through the washing water reservoir in a closed coil so that it is not permitted to mingle with the washing water.

35 Other objects and advantages will be apparent as the invention is better understood by reference to the following description when considered in connection with the accompanying drawings, on which—

40 Figure 1 is a diagrammatic side elevation of a boiler washing and filling system embodying my invention; and Fig. 2 is a side elevation of a modified arrangement.

Referring to the drawings and, particularly, to Fig. 1, 5 indicates a washing water reservoir and 6 a refilling water reservoir. In this modification the two reservoirs are embodied in a single tank divided by a partition 7. The roundhouse is equipped with 50 the usual blow-off line 8, washout line 9 and refilling line 11, which are connected adjacent each pit of the roundhouse with suitable drop terminals 12 and through which communication is established with the locomotives to be blown off, cleaned and refilled.

Ordinarily the wash water which flows from the boilers being washed into the pits 13 is conducted to a sewer and permitted to escape, but my present invention contemplates the saving of this wash water and the utilization of the same again for washout purposes. To this end I have provided a sump 14 to which the wash water is conducted from the pits by a conduit 15. In order that the water may be cleansed before being used again, I provide a settling chamber 16 into which the wash water is first discharged and wherein the scale, sludge, mud and other heavy sediment is settled, so that the water flowing through the partition 17 into the sump proper is comparatively clean. A pump 18 actuated from a motor 19, or other suitable source of power which, preferably, is automatically controlled from a float 21 through suitable controlling mechanism, electrical or otherwise, so that the pump will be stopped when the sump is empty, is adapted to deliver water from the sump through a pipe 22 to the washing water reservoir 5. The wash water which has, heretofore, been wasted, is, by means of this construction, cleansed and then delivered to the washing water reservoir where it is heated and then delivered by a washout pump 23 which receives its suction 70 through the pipe 24 to the washout main 9. The pump suction may be controlled by a hand-valve 25 in the usual manner. Since the quantity of wash water in the sump may sometimes be insufficient for washout purposes, I have provided an auxiliary water supply pipe 26 adapted to deliver water to the washing water reservoir. A valve 27 interposed in the pipe 26 and automatically controlled by a float 28 located in a float chamber 29 connected with the washing water reservoir controls the supply of water so that a predetermined water level is maintained in the reservoir. A suitable overflow pipe 31 is provided for the reservoir and the inner end of the pipe is extended downwardly beneath the water level to prevent the escape of steam from the reservoir. A vent pipe 32 connected with the crown of the overflow prevents the emptying of the reservoir by siphonic action and also serves to prevent collapse of the reservoir in case of the formation of a vacuum therein, this function being augmented by a small projection or nozzle 33 formed on the overflow 80 85 90 95 100 105 110

coupling inside the reservoir and preferably equipped with an outwardly opening check-valve so that air may be admitted to the reservoir through the vent pipe 32, 5 the crown of the siphon and the nozzle 33, when necessary, but steam can not escape from the reservoir. The overflow pipe communicates with the sewer 34 through a suitable connecting pipe 35.

10 In the present system the washout water in the washing water reservoir is heated by the blow-off water from the locomotives but, instead of using the blow-off water directly for wash water as is done in some systems, I 15 prefer to utilize the heat units of the blow-off water without using the water itself, thus preventing contamination of the washout water by the sludge, scale and other undesirable substances contained in the blow-off 20 water. I, therefore, conduct the blow-off water through the washing water reservoir in a closed coil 36 by means of which the heat of the blow-off water is conveyed to the water in the reservoir without mingling 25 the blow-off water therewith. The delivery end of the coil is connected with the pipe 35 through which the water is discharged to the sewer. In order to remove the larger pieces of scale and sludge from the blow-off 30 water so that the same will not accumulate in the coil 36 and clog it up, I prefer to connect the blow-off main with a scale pocket or sludge chamber 37 into which the blow-off water is directly discharged and from which 35 it flows through the pipe 38 to the coil 36. A discharge pipe 39 controlled by a hand-valve 41 permits the deposit in the scale pocket to be discharged directly to the sewer whenever it may become necessary or desirable to clean the scale pocket. It will 40 be noted that the intake end of the pipe 38 projects downwardly in the scale pocket beneath the water level so that any blow-off steam which may be discharged into the 45 scale pocket will be prevented from escaping to the sewer through the coil.

The blow-off steam is conducted from the blow-off main through a branch pipe 42 to the filling water reservoir 6 where it is discharged beneath the surface of the water 50 through a plurality of branches 43 for the purpose of heating this water. The refilling water before it is supplied to the refilling reservoir 6 is preliminarily heated in a feed water heater 44 by exhaust steam from the refilling and washout pumps and from the power house delivered to the heater through the pipe 45. Water is supplied to the heater 55 through a supply pipe 46 equipped with a float valve 47 which is controlled from a float 48 situated in a float chamber 49 communicating with the heater, as shown. A pipe 51 conducts the water which is preliminarily heated in the heater 44 to the filling 60 reservoir 6 and a branch pipe 52 also con-

ducts water to the power boilers, the heater 44 thereby serving both as a preliminary heater for the filling water and also as a feed water heater for the power boilers. The steam rising uncondensed from the feed water heater is conducted by a pipe 53 to the pipe 42 by which it is delivered through the branches 43 to the water in the filling water reservoir for heating the same, thereby utilizing all of the exhaust steam. A vent pipe 75 54 equipped with a safety or excess pressure valve 55 serves to permit the escape of steam when the pressure in the feed water heater and filling water reservoir reaches a predetermined point. In order to prevent the water 80 in the filling water reservoir from falling below a predetermined temperature in the event of a deficiency in the supply of exhaust steam or blow-off steam, I have provided a pipe 56 connected with a live steam supply pipe 57 through which live steam 85 may be admitted to the filling water reservoir. A thermostat valve 58, controlled from the thermostat 59 within the filling water reservoir, permits the admission of steam 90 when the temperature of the water falls below a predetermined point. A similar pipe 61 discharging into the washing water reservoir is connected with the power house exhaust pipe 45, the admission of steam 95 to the washing water reservoir being controlled by a thermostat valve 62 actuated from a thermostat 63 in the washing water reservoir. In order that either live or exhaust steam may be supplied to both the 100 washout and refilling water reservoirs, I have connected the pipes 61 and 56 by a connecting pipe 64 equipped with a hand-valve 65 which may be opened, to permit exhaust steam to be supplied to the filling 105 water reservoir through the pipe 56, or, to permit live steam to be supplied to the washing water reservoir and, also, to the feed water heater, if desired. A check-valve 66 interposed in the power house exhaust pipe 110 45 prevents live steam from flowing back toward the power house when the valve 65 is opened.

A circulating pipe 67 is connected with the end of the washout main and returns 115 to the washing water reservoir so that a continuous circulation of the wash water is maintained by the pump 23. A similar circulating pipe 68 is connected with the end of the refilling main 11 and discharges 120 into the top of the feed water heater 44, so that a continuous circulation of the water in the refilling main is maintained by the refilling pump 69 which receives its suction from the filling water reservoir 6 125 through a pipe 71. The suction to this pump may be controlled by the valve 70 in the usual manner. The washing water reservoir and the filling water reservoir are connected with the pipe 35 by means of a 130

pipe 72 equipped with valves 73 and 74, respectively, through which these reservoirs may be cleaned out when desired.

The system disclosed in Fig. 2 is substantially similar to that disclosed in Fig. 1 and the operation is practically identical. The washout and refilling water reservoirs 5 and 6, however, are constructed independently of each other and may be mounted 10 side by side as shown in Fig. 2, this arrangement being preferable in some installations where the small space will not permit the installation of a long tank such as is disclosed in Fig. 1. The feed water heater 15 44, in this instance, also is mounted above the filling water reservoir 6 and the settling tank 16, instead of being made a part of the sump 14, is constructed separately therefrom and connected therewith by a 20 pipe 75. In other respects the systems are substantially alike except for such changes in the pipe connections and position and arrangement of pipes as is required by the different disposition of the reservoirs and 25 heater.

In the operation of my improved system the wash water from a locomotive which is discharged into the pits is collected in the sump 14 from which it is delivered to the 30 washing water reservoir 5 after being cleansed, wherein it is heated by the blow-off water passing through the coil 36, after which it is delivered to the washout line by the pump 23. A predetermined temperature 35 of the washout water is maintained by live or exhaust steam admitted through the pipe 61. The refilling water is preliminarily heated in the feed water heater 44 from which it is delivered to the filling 40 water reservoir 6 where it is further heated by the blow-off steam delivered thereto by the pipe 42, the temperature of this water being maintained by live or exhaust steam admitted by the pipe 56. The filling water 45 is delivered to the refilling main by the pump 69 and a circulation is maintained in both the washout and refilling mains through the circulating mains 67 and 68.

It is believed that my invention will be 50 understood from the foregoing without further description and, while I have shown and described preferred constructions and arrangements of pipes, it will be obvious that various modifications in details of construction may be resorted to within the scope 55 of my invention and without sacrificing any of its material advantages.

I claim:

1. In a boiler washing and filling system, 60 the combination of a washing water reservoir, a filling water reservoir, means for supplying water to said washing water reservoir, means for supplying water to said filling water reservoir, a blow-off main, 65 means for separating the blow-off steam

and water, means for conducting the separated blow-off steam to the refilling reservoir to heat the water therein, and means for conducting the separated blow-off water through the washing 70 water reservoir to heat the washing water therein without mingling the blow-off water therewith.

2. In a boiler washing and filling system, the combination of a washing water reservoir, a filling water reservoir, a feed water heater, means for delivering water from said feed water heater to the filling water reservoir, means for supplying water to the washing water reservoir, means for conducting blow-off steam to the filling water reservoir for heating the water therein, means for conducting blow-off water through the washing water reservoir for heating the water therein without mingling 80 the blow-off water therewith, means for delivering water from the washing water reservoir to a roundhouse for washout purposes, and means for delivering water from the filling water reservoir to a roundhouse 85 for refilling purposes.

3. In a boiler washing and filling system, the combination of a washing water reservoir, a sump, roundhouse pits, means for conducting washout water from the roundhouse pits to said sump, means for delivering water from said sump to the washing water reservoir, and a closed coil disposed in said washing water reservoir whereby blow-off water from a boiler is conducted 95 through said reservoir to heat the water therein without being mingled with said water.

4. In a boiler washing and filling system, the combination of a washing water reservoir, a sump, roundhouse pits, means for conducting washout water from the roundhouse pits to said sump, means for delivering water from said sump to the washing water reservoir, an auxiliary pipe for supplying 100 water to said washing water reservoir, means for conducting blow-off steam and water from a locomotive boiler, and means for separating the blow-off water from the blow-off steam and conducting said water through the washing water reservoir, whereby the washing water in said reservoir is heated from the blow-off water of the boiler without being mingled therewith.

5. In a boiler washing and filling system, the combination of a washing water reservoir, a filling water reservoir, means for supplying water to said filling water reservoir, a sump, roundhouse pits, means for conducting washout water from the roundhouse pits to said sump, means for delivering water from the sump to said washing water reservoir, means for mingling blow-off steam with the water in the filling water reservoir to heat the same, and means for 120 125 130

conducting blow-off water through the water in the washing water reservoir to heat the same without mingling the blow-off water therewith.

- 5 6. In a boiler washing and filling system, the combination of a washing water reservoir, a filling water reservoir, a feed water heater, a pipe for supplying exhaust steam to said feed water heater, a pipe for conducting partially heated water from said feed water heater to the filling water reservoir, roundhouse pits, a sump adapted to receive water from the roundhouse pits, means for cleansing said roundhouse water, a
- 10 15 pump for delivering water from said sump to the washing water reservoir, means for conveying blow-off steam to the filling water reservoir for heating the water therein, means for conducting blow-off water
- 20 25 through the washing water reservoir to heat the washing water without being mingled therewith, means for delivering water from said washing water reservoir to a roundhouse for washout purposes, means for delivering water from the filling water reservoir to a roundhouse for refilling purposes,

and means for maintaining a circulation in the washout and refilling lines.

7. In a boiler washing and filling system, the combination of a washing water reservoir, a refilling water reservoir, a sludge chamber, a blow-off line connected with said sludge chamber, means for conducting blow-off water from said sludge chamber through said washing water reservoir without mixing the same with the water in the reservoir, a pipe connected with the blow-off line for conducting blow-off steam to said refilling water reservoir, means for supplying clean fresh water to said refilling water reservoir, a heater for preliminarily heating the water delivered to said refilling water reservoir, a sump, round house pits connected with said sump, means for delivering water from said sump to said washing water reservoir, a refilling line connected to said filling water reservoir, and a washout line connected to said washing water reservoir.

FRANK W. MILLER.
